UNITED STATES PATENT OFFICE.

THORWALD THORSON, OF FOREST CITY, AND EDWIN O. THORSON, OF AKRON, IOWA.

REFRIGERATOR.

Substitute for application Serial No. 500,396, filed September 13, 1921. This application filed February 7, 1924. Serial No. 641,312.

To all whom it may concern:

Be it known that we, THORWALD THORSON and EDWIN O. THORSON, citizens of the United States, and residents of Forest City

5 and Akron, in the counties of Winnebago and Plymouth and State of Iowa, respectively, have invented a certain new and useful Improved Refrigerator, of which the following is a specification.

10 The object of our invention is to provide a simple, durable and comparatively inexpensive device for handling brick ice cream and similar articles in connection with a refrigerator container, in such a manner that 15 the bricks may be easily and quickly removed from the container without admitting warm air to the container.

A further object is to provide an attachment which may be installed in refrigerators 20 in the nature of a magazine in which cartons of ice cream or similar articles may be placed within the refrigerator, and when so placed they may be withdrawn one at a time without having to open the refrigerator door, the withdrawing device being so arranged that a comparatively small amount 25 of warm air will be admitted by the operation of said withdrawing device.

These and other objects will be apparent 30 to those skilled in the art.

Our invention consists in the construction, arrangement and combination of the various parts of the device, whereby the objects contemplated are attained, as hereinafter more 35 fully set forth, pointed out in our claims, and illustrated in the accompanying drawings, in which:

Figure 1 is a front elevation of a refrigerator with our improved device installed.

40 Figure 2 is a vertical sectional view of the same taken on the line 2—2 of Figure 1.

Figure 3 is an enlarged detail sectional view taken on the line 3—3 of Figure 2.

Figure 4 is a sectional view taken on the 45 line 4—4 of Figure 3.

Figure 5 is a detail sectional view taken on the line 5—5 of Figure 3.

Figure 6 is a sectional view taken on the line 6—6 of Figure 3.

50 The numeral 10 indicates the walls of a refrigerator which is preferably provided with a chamber 11 at its bottom, and a chamber 12 at its top. The chamber 11 is provided with a refrigerating device 13.

55 This device is provided with upstanding

pipes 14 which are in communication with the cooling member 15. This cooling member is mounted on the interior of the chamber 12 and at its back portion.

The chamber 12 is provided with a door 16 60 which is constructed similar to those of the ordinary refrigerators. A door 17 is provided in the walls of the lower chamber 11 through which the operator may adjust the machinery of the device 13. The refrigerator 13 and the cooling member 15 may be of any ordinary construction, and form no part of my present invention. Ice might be substituted for the cooling member 15 if it is so desired. 70

In front of the member 15 we have provided vertical guide members 18 and 19, so arranged and spaced that they will form a series of hoppers in which cartons of ice cream may be placed. 75

The members 18 are provided with a flat portion 20, each edge of which is provided with a rearwardly extending flange 21. The back edge of the flange 21 is provided with a laterally extending portion 22, the members 21 and 22 being designed to receive the corners of the carton and to form guide members therefor, as the said cartons are moved downwardly. 80

The members 19 are each provided with a flat portion 23, each of its edges having a rearwardly extending portion 24, the said portion 24 being designed to engage the front side edges of the carton. The members 24 are in line with the members 21, and the members 23 being of a width equal to the width of the member 20. Any number of these members 18 and 19 may be mounted in the refrigerator as desired. 85

By this arrangement it will be seen that the members 18 and 19 may be made to form a sort of hopper in which a series of cartons of ice cream or similar articles may be placed by being moved rearwardly between the members 24 until they engage the member 22 and between the members 21. 90

Slidably mounted on the bottom of the chamber 12 and between each set of members 19 and 20, we have provided a drawer 25. This drawer 25 is provided with a bottom, 105 and side members 26, a back end member 27 and a front end member 28. The back end member 27 is provided with a block of heat insulating material 29, this block being provided with a shoulder 30 on its inner face, 110

the purpose of which will hereinafter be made clear.

The front end member 28 is provided with a heat insulating block 31, and also with a handle 32. The said drawer 25 is slidably mounted in an opening 33, the said opening and the member 28 being provided with suitable seal plates 34 so arranged as to interlock each other when the member 28 is 10 within the opening 33.

The drawer 25 is of a width slightly greater than the width of the bricks, and so arranged that the bricks on the magazine may enter between the said members 26, and 15 just in front of the member 32 when the drawer is in its inward limit of movement.

The space between the members 19 and the front walls of the refrigerator is provided with a horizontally arranged tube 35^a, the 20 upper plate 35 being secured at a point just above the top edge of the members 28 and 31, and provided at its rear edge with an upwardly and forwardly extending flange 36, this flange 36 being so arranged as to form a 25 guide plate for the cartons as they descend between the guide members 18 and 19, and to force any brick that should not be against the members 22 backwardly.

The tube 35^a forms a seal to prevent warm 30 air from entering the chamber 12, as will hereinafter be more fully set forth.

By the arrangement just described, it will be seen that if the handle 32 is grasped and the drawer 25 is drawn outwardly, that the 35 carton within the drawer would also be drawn out through the tube 35^a, but some means must be provided for holding the rest of the bricks against downward movement while this outward movement of the drawer 40 takes place.

To accomplish this, we have provided two parallel and horizontally arranged rock shafts 37 and 38, which are rotatively mounted in the members 20 and 23, as 45 clearly shown in Figures 3 and 4, the shaft 38 being longer than the shaft 37 and designed to extend forwardly through the front walls of the chamber 10, and at a point above the drawers 25.

The forward end of each of the shafts 38 is provided with a handle 39 arranged preferably in a horizontal position, as clearly shown in Figure 1, so arranged that as the said handle is moved upwardly and downwardly, a rotary movement may be imparted 55 to the shaft 38.

The forward end of the shaft 37 is mounted in the forward wall of the container 12. The forward end of the shaft 37 is provided 60 with a bell crank lever 40.

Each of the shafts 38 is provided with a rock arm 41 adjacent to the forward wall of the chamber 12. This rock arm extends downwardly and is provided with a pivotally connected link 42, the opposite end of

which is pivoted to the upwardly extending arm of the bell crank 40, as clearly shown in Figure 5. The opposite arm of the bell crank 40 is provided with a downwardly extending link 43, the lower end of which is provided with a grooved roller 44. The groove of the roller 44 is designed to rest normally on the edge of a notch 45 in one of the plates 26, as clearly shown in Figure 4. The member 43 is slidably mounted in the 75 top member of the tube 35^a.

The bell crank 40 and the plate 35 form bearings which will permit the rod 43 to slide vertically, but will prevent the roller 44 from being moved in a horizontal plane. 80 This forms a lock device which will prevent the drawer 25 from being opened except when the handle 39 is elevated, in which case the roller 44 will be drawn out of the notch 45, and will rest on the upper edge of the member 26 after the drawer has been slightly moved forwardly.

Each of the rods 37 and 38 is provided at its central portion between the members 18 and 19 with what we shall term a clutch 85 device for holding the column of cartons against downward movement. Only one of these devices, however, will be described as all of them are alike.

Each of these devices comprises an arm 46 rotatively mounted on said shaft, the free end of which is provided with a pivoted link 47. The said link 47 is in turn pivotally connected to a block 48. The face of the said block may be serrated at 49 or provided with a resilient contact member. 95

The link 47 is provided with an inwardly and upwardly extending curved portion 50. This member 50 is designed to be engaged by a pin 51 extending radially from the shaft 38 in such a manner that as the said shaft 38 is rotated, the pin 51 will be moved laterally causing the link 47 to be rocked about the pivot with which it is connected to the arm 46, and the block 48 moved inwardly and outwardly. Movement is imparted to the arm 46 by the pins 51 and the pins 52 extending from the member 46. 105

The free end of link 47 is yieldably held to its outward limit of movement by means of a spring 53, one end of which is made to partially surround the shaft 37, while the other is designed to engage the pin 54 extending from the link 47, as clearly shown in Figure 5. 110

The blocks 48 are designed to rest normally with their faces adjacent to the side faces of the second carton of ice cream from the bottom of the column when they rest in the drawer 25, as clearly shown in Figure 4, the said blocks being yieldably held in contact with the said faces of the springs 53. 120

The operation of our device is as follows: Assuming that the operator wishes to fill the magazine with brick ice cream or any 125

material which may be in rectangular cartons, and it is desired to keep it cool, he opens the door 16 and places the cartons endways between the flanges 24 of the members 19, and moves them rearwardly until the rear end of said cartons engage the flanges 22. As many of these cartons or bricks may be placed in the guides as is desired until they are filled, after which the door 16 may be closed and does not need to be opened until after the magazine has been emptied.

The drawers 25 should always be in the closed position, in which case the bottom 15 carton or brick of each vertical column will rest in a corresponding drawer.

In actual practice the device is considered emptied when but only the two bottom 20 bricks or cartons remain in the column, as this eliminates the necessity of having to place the cartons in between the blocks 48 as is necessary the first time the device is filled, as this will be taken care of automatically thereafter.

If it is desired to remove one of the 25 cartons, the lever 39 is elevated, which will cause the shaft 38 to be rocked, and also the corresponding shaft 37 by the corresponding link 42. These shafts will be rotated in opposite directions as indicated by the arrows 30 in Figures 5 and 6. This movement will cause the lower ends of the arms 46 to be elevated, which in turn will cause the blocks 48 to be elevated, and the cartons or bricks 35 between the said blocks elevated, and the entire column of bricks above the said brick to also be elevated. This elevation need be only enough to relieve the pressure from the brick within the drawer 25.

As the handle 39 is elevated, the handle 32 is grasped with the opposite hand and the drawer 25 pulled outwardly. The upper edge of the member 26 will then extend beneath the roller 44 and lock the members 48 in contact with the cartons. The drawer 25 may then be moved outwardly to its extreme 45 limit of movement and the carton within the drawer moved outwardly, after which the carton may be removed when the drawer is at its outward limit of movement. The member 29 will rest in the opening 33 and thereby prevent the cool air within the chamber from escaping and warm air from entering. When the brick has been removed, the drawer 25 may then be pushed back 55 into the chamber 12. The roller 44 will then drop in the notch 45 which will cause the pin 51 to engage the member 56, and the blocks 48 to be released from the sides of the carton. The cartons will then be permitted to drop to the bottom of the drawer 60 25.

The drawers 25 will also be locked against outward movement until the lever 36 has 65 been actuated, thereby providing a safety

device to prevent the drawer from accidentally becoming open.

We claim as our invention:

1. A cooling chamber having an opening 70 communicating with its interior, a door for said opening, a drawer slidably mounted in the bottom of said chamber adapted to be slid from a position within the chamber to a position outside of the chamber, a magazine in said chamber adapted to contain a 75 vertical column of cartons in such a manner that the bottom carton of said column will rest in said drawer when it is in its inner limit of movement, means for gripping a portion of the cartons in said column and slightly elevating them and retaining them in the elevated position as the said drawer is moved to its outward limit of movement, and means outside of said chamber for operating the last said means.

2. A cooling chamber having an opening 80 communicating with its interior, a carrier slidably mounted in said opening to slide from a position within the chamber to a position outside of the chamber, a magazine 85 having one end in communication with the carrier and adapted to contain a vertical column of cartons in such a manner that the bottom carton of the column will rest in said carrier when in its inner limit of movement, means for gripping a portion of the cartons in said column to slightly elevate them and retain them in said elevated position as the said carrier is moved to its outer limit of movement, and means outside of said chamber 90 for operating the last said means.

3. A cooling chamber having an opening 95 communicating with its interior, a magazine within the container designed to receive a vertical column of cartons, a carrier for moving one of the cartons of said column through the said opening, means for elevating and retaining a portion of the cartons of said magazine in a slightly elevated position while the carrier is being actuated, and means outside of the container for actuating the last said means.

4. A cooling chamber having an opening 100 communicating with its interior, a magazine within the container designed to receive a vertical column of cartons, a carrier for moving one of the cartons of said column through the said opening, means for elevating and retaining a portion of the cartons of said magazine in a slightly elevated position while the carrier is being actuated, and means outside of the container for actuating the last said means, and means actuated by the cartons elevating means to lock the carrier in its inner limit of movement.

5. A cooling chamber having a pair of 115 openings communicating with its interior, a door for one of said openings, a carrier adapted to be moved from a position within said container to a position outside of said

- 4
- 5 container, through the last said opening, and to close the said opening when it is in its inner and outer limit of movement, means for supporting a vertical column of cartons in operative relation with said carrier in such a manner that the lower ones may be successively removed, means for gripping and supporting a portion of the cartons of said column against downward movement
- 10 10 as the lower one of said cartons is being removed, and means on the outside of said container for actuating the last said means and for locking the said carrier against movement when it is in its inner limit of movement.
- 15 6. A cooling chamber having an opening through which material may be placed in the chamber, a door for said opening, the
- 20 said chamber being provided with a series of smaller openings, a drawer for each of said smaller openings adapted to be moved from a position within said chamber to an outwardly extending position, a group of vertical guide members for each of said drawers arranged to slidably receive a vertical column of cartons in such a manner that the lower one of said cartons will rest in said drawer, clamping means for engaging the second carton from the bottom, and means for actuating said clamping means in such 25 a manner that the said second carton will be slightly elevated and retained against downward movement as the said drawer is moved to its outer limit of movement.
- 25 30 THORWALD THORSON.
EDWIN O. THORSON.
